UNITED STATES PATENT OFFICE.

ALONZO C. BALLOU, OF LYNCHBURG, VIRGINIA.

DUMPING-BODY.

1,300,810.

Specification of Letters Patent. Patented Apr. 15, 1919.

Application filed April 29, 1918. Serial No. 231,401.

To all whom it may concern:

Be it known that I, ALONZO C. BALLOU, a citizen of the United States, residing at Lynchburg, in the county of Campbell and State of Virginia, have invented certain new and useful Improvements in Dumping-Bodies, of which the following is a specification.

This invention relates to dumping bodies for railway cars, mining cars and automobile trucks, and particularly to the dumping mechanism for such bodies.

A principal object of this invention is to provide a dumping mechanism for cars and trucks which will dump from either side with equal ease.

Another object is to provide a dumping mechanism which will first open the side of a car fully, then will dump the load, with the open side acting as a chute for the material.

A third object is to construct a dumping body either of whose sides may be held open to facilitate cleaning or repairing without dumping the body.

A further object is to make a dumping car which will be adaptable for handling a great variety of materials, such as dirt, sand, ore, crushed rock, and grains and vegetables.

In order to attain these objects, I construct the dumping body somewhat as shown in the drawings which accompany and form a part of this specification. It is to be understood, however, that a drawing is necessarily somewhat diagrammatic in character and that the dictates of what is known as good design are not always followed. The accompanying drawing is to be regarded then as merely illustrative, and is not to be considered from any other viewpoint. I may wish to depart materially from the drawing in many details to obtain a superior form of dumping body and wish to be limited only by the claims hereto appended.

In the drawing—

Figure 1 is an end elevation of one embodiment of my invention, showing in dotted lines the dumping position of the body;

Fig. 2 is a similar view of the opposite end of the body showing the parts in locked position;

Fig. 3 is a side elevation of the dumping body;

Fig. 4 is an end elevation of the same with parts broken away showing the body in the act of being dumped;

Fig. 5 is a sectional elevation taken on the line 5—5 of Fig. 3, looking in the direction of the arrow;

Fig. 6 is a detail elevation, partly in section, showing the dumping lever in neutral position on the body;

Fig. 7 is a perspective showing the dumping lever and its connecting levers; and

Fig. 8 is a bottom plan view of the frame which supports the dumping body, this view being on a reduced scale.

Referring to the drawings, A designates a supporting frame and B a carrier or tilting body held upon the frame.

The numeral 10 designates the two side members and 11 the two end members of the rectangular frame A. (See Fig. 8). Four spaced cross-pieces 12 in groups of two, one group near each end of the frame A and secured thereto, are also provided. These cross-pieces are lighter than the frame members, and are provided not only to strengthen the frame, but to support and receive rocking arms or links, as will be seen. The rocking arms or links mentioned are designated by the numeral 14, and are pivoted at their lower ends to bolts 13 which pass through the ends of the cross-pieces 12. The upper ends of the rocking arms or links 14 are pivoted by bolts 14' which are secured to the dumping body proper beyond the sides.

There are two pairs of the rocking arms 14, corresponding to the two pairs of cross-pieces 12, the arms of each pair crossing each other as shown. These arms are the connecting links or medium between the frame A and the body B, and being of equal length and free to move about their axes, allow the body B to swing to either side of the frame. At the same time, these rocking arms prevent the body from swinging farther than is desirable, that is, farther than about sixty to seventy-five degrees, swinging into contact as they do with the frame A between the cross-pieces 12, as shown in Fig. 1.

The body B is rectangular in plan, just as its frame is, and includes the solid bottom 17, the rigid ends 18 and the hinged sides 19, the top of course being open. The bottom 5 17 is held upon braces 16 which run cross-wise thereunder in two pairs, one near each end of the body, said braces extending a short distance beyond each side of the body as shown. The bolts 14' pass through the 10 ends of the braces 16, which are spaced apart from each other so as to include the ends of the rocking arms 14. It will be seen that the braces 16 and the cross-pieces 12 are 15 analogous in function, the former providing attaching means for the upper ends of the rocking arms or links to the body, the latter providing attaching means for the lower ends of said arms to the frame. Spacing sleeves 13' mounted on bolts 13, and similar 20 sleeves 16' on bolts 14', are employed to maintain the rocking arms 14 in their proper position upon their axes during dumping.

It will be understood that the sides 19 of the body are the only parts which swing 25 outwardly prior to the actual dumping operation. These sides 19 each have rigidly secured to them legs 15 which are pivoted near their middle points upon the bolts 14'. These legs being secured to the sides 19 30 swing with the latter until they come in contact with the bottom 17 of the body thus serving as stops. Then the sides can move no farther, and are held in the plane of the bottom 17 so as to act as a chute for the material dumped. All this is clearly seen in 35 Fig. 4. In the normal position of the body, the legs 15 rest upon the outer cross-pieces 12 as Fig. 3 indicates. When so resting they hold the body in place upon the frame and 40 prevent premature dumping. The legs do not meet the cross-pieces perpendicularly but at an angle. As Fig. 3 shows, the legs 15 swing between the sleeves 16' and the extended ends of the braces 16. Hence, each 45 of the bolts 14' holds together the ends of two braces 16, one rocking arm 14, one leg 15 and one sleeve 16'.

One of the ends 18 of the body B is provided on its upper edge 18' with projections 50 or teeth 20 for interlocking engagement with the actuating mechanism to be described. Said projections may have any desirable contour. In the illustrated embodiment of my invention (see Fig. 6) they are shown 55 as having an edge 23 which rises at right angles above upper edge 18', and an edge 22 which diverges downwardly with respect to edge 23, thus producing the irregular quadrilateral projection or tooth 20 which the 60 drawing illustrates. These teeth are preferably formed integrally with the end 18, thus assuring strength and rigidity. The upper edge of end 18 between teeth 20 is cut out so as to be below the level of edge

18', thus providing a seat 21 for the reception of the dumping lever and connected parts. 65

The actuating mechanism consists of a dumping lever 27 with a flared base 28 for strength, secured by rivets or pins 26 to a 70 rocking frame, which rests upon the edges 18' and in the seat 21. This rocking frame is rectangular in general outline, being made up of bars 24, connected together near each end as at 25. When the dumping lever 75 stands in an upright position, the rocking frame at its base lies upon the edge 18' bearing thereupon near each end outside the teeth 20, the bars 24 inclosing the teeth. When the lever is rocked in either direction, 80 one end of the frame will be lifted and will swing about the other end as an axis, which Fig. 4 clearly illustrates.

As was said above, the frame 24 is held at each end by parts 25. Now these parts 25 are the inturned ends of two bent rods 29 which connect the operating lever with the sides of the body and hence provide means for the dumping thereof. Each rod 29 is pivoted at one end 25 to the frame 24, has a 90 transverse portion 30 extending along the end of the body, and a longitudinal portion 31 extending at right angles to 30 along the side of the body and through bearing openings 15' in the legs 15. The opposite end 95 of portion 31 remote from the operating lever is bent at right angles to form the transverse portion 32 which is also parallel to portion 30. The extreme end of portion 32 is bent to form a hook terminal 33, 100 which engages with a pin 34 jutting from the end 18. The elements 33 and 34 constitute a latching means for the sides when in closed position. Recesses 20' are provided in the upper edge 18' of the end 18 105 adjacent the teeth 20 to receive the inturned ends 25 of the rods 29 so that said ends riding in said recesses constitute the fulcrums on which the frame 24 swings.

The operation of the above-described 110 parts will now be clear. When the lever 27 is pulled in either direction, the frame 24 will rock on the fulcrums 20', and release the hook terminal 33 from the pin 34. Continued movement of the lever will force one 115 of the sides 19 open, turning by means of its legs 15 upon 14' as an axis. The other side 19 will be held tightly closed. The other rod 29 will hold the lever with the fulcrum 25 in the recess 20' and will remain 120 secured at its end 33 to its pin 34. When the legs 15 swing against the underside of the body, the side 19 can move no farther, and it extends out in the position shown in Fig. 4. When the side lets down, a portion 125 of the load rolls out on the side giving added weight to that side, and with a light pressure downwardly on the side the body

is completely dumped. After discharging the load, a light lift on the side causes the body to assume its former position with the two legs 15 resting upon the cross-pieces 12. Then a swing of the lever will close the side 19, cause the bar frame 24 to interlock with the teeth 20, and the hook end 33 to close down upon the pin 34. The other two legs 15 will now rest upon the cross-pieces 12, and the body will be in the position shown in Fig. 1. The drawing illustrates a dumping body most of whose parts are of wood. It will be clear that I can employ metal in part or throughout the body without departing from my invention. Such employment will be necessary when constructing dumping cars which are to carry heavy or abrasive material such as sand. On the other hand, wood might be a more desirable material when handling loose earth, vegetable products, etc.

Various changes might be made in the shape of the teeth 20, or in the size thereof to insure interlocking of the rocking frame 24 therewith. Moreover, the ends of the legs 15 instead of being finished straight might be made rocker-shaped to reduce the friction with the cross-pieces 12 when starting to dump. Rollers might be placed on the ends of these legs with the same idea in mind. A great many other changes in arrangement, form and construction of the various parts might be resorted to to improve upon the construction illustrated. I wish to claim as my right to make all such changes which come fairly within the realm of mechanical skill.

With this understanding, what I claim is—

1. A dumping body comprising a frame, a body tiltable on the frame, swingable sides on the body, and an actuating mechanism for the sides, said mechanism including a manually operable lever, rods connecting the lever to the sides, and latching means for said rods, said sides being held closed by the latching means when the lever is in neutral position and being manipulated singly by the movement of said lever to either side of the neutral position.

2. A dumping body including a frame, a tiltable carrier body mounted upon the frame sides pivotally carried by said body, legs secured to the sides and extending below to the frame, said legs supporting the body when in the neutral position and acting as stops for said sides when the body is being dumped, and a lever-operated mechanism connected with said sides and co-operating with the legs to swing either side open into the plane of the bottom of said body and hold the other side in place, the arrangement being such that but one side can be swung at one time.

3. A dumping body including a frame, a

tiltable carrier body mounted upon the frame, sides pivotally carried by said body, and actuating mechanism connected to said sides, said mechanism providing means for opening either of the sides and holding the same fixed relative to the body while the body is tilted, said sides when open forming a continuation of the bottom of the body and serving as a chute and stops secured to each side and operating to automatically engage with the underside of the body to hold the sides in alignment with the bottom thereof.

4. A body for dumping material including a frame, a pair of swingable crossed links pivoted near each end of the frame, a carrier body pivoted to the upper ends of said crossed links, swingable sides on said body, legs secured to the sides and turnable about the axes of the upper ends of the crossed links, said legs normally standing on the frame, and an actuating mechanism connected with the sides.

5. A dumping body comprising a frame, a carrier body tiltable thereon, and an actuating mechanism, said frame including two pairs of cross-pieces fixed thereon, one pair near each end of the frame, pivots extending between the ends of each pair, said carrier having two pairs of braces underneath its bottom and extending beyond the sides thereof, the braces corresponding to the cross-pieces and having similar pivots at their ends, and crossed links at each end of the body, said links having openings near their ends and receiving the pivots in said openings.

6. A dumping body comprising a frame, a body, crossed links arranged in pairs at spaced points, means for pivotally connecting the links to the frame, means for pivotally connecting the links to the body at points beyond the sides of the body, said body having a rigid bottom and ends and sides pivoted thereto by said second-named means, means for opening either of the sides, means for limiting the swinging movement of the sides so that they assume a fixed position when brought into substantial horizontal alignment with the bottom of the body, said means being brought into engagement with the frame when the sides are in closed position to support the body above the frame independently of the links.

7. A dumping body comprising a frame, a body tiltable on the frame, swingable sides on the body, and an actuating mechanism, said mechanism including a manually operable lever, and rods connecting the said lever to said sides, said lever having two fixed axes from either of which the nearer side is manipulated.

8. A dumping body comprising a frame, a carrier body having swingable sides tiltable thereon, and an actuating mechanism,

4
said mechanism including a hand-operated lever connected with said sides, said lever having two fixed axes from which the two sides are manipulated and between which it 5 is shiftable.

9. A dumping body including a frame, a carrier body tilttable on the frame, and having swingable sides and fixed ends, and bottom, and an actuating mechanism, including 10 a hand-operated lever seated upon one of the ends of the carrier body, said end having interlocking means projecting above its upper edge for engagement with a frame secured to the lever.
- 15 10. A dumping body including a frame, a carrier body tilttable on the frame, said body having fixed ends and bottom and swingable sides, and an actuating mechanism including a lever, interlocking teeth projecting above 20 the upper edge of one of said ends for engagement with the lever, said lever being shiftable upon said edge so as to engage either tooth separately during the dumping operation, and a linkage connecting the lever 25 with the swingable sides.

11. A dumping body including a frame, a carrier body tilttable on the frame, said body having fixed ends and bottom and swingable sides, and an actuating mechanism, including 30 two teeth projecting above the upper edge of one of the said ends, a lever connected with both of the swingable sides, and a frame joined to the base of the lever, each end of said frame interlocking with one of 35 said teeth.

12. A dumping body including a frame, a carrier body tilttable upon the frame, said body having fixed ends and bottom and swingable sides, and an actuating mechanism, including 40 two tooth-like projections provided upon the upper edge of one of the body ends, each of said teeth presenting an outer edge perpendicular to the edge of the body end, and a lever connected with the 45 swingable sides, said lever having a rocking frame secured to its base, said frame when the lever is rocked bearing against the outer edge of the tooth.

13. A dumping body including a frame, a carrier body tilttable upon the frame, and having movable sides and an actuating mechanism, including a hand operated lever, a flared base forming a part of said lever, a rocking frame secured to said base, means 55 upon said body engaging with said rocking frame to permit the rocking thereof, and means joining the lever to said sides of the body by which the sides may be tilted.

14. A dumping body including a frame, a carrier body tilttable upon the frame and having swingable sides, and an actuating mechanism, including an operating lever provided with a flared base, a rocking frame secured to and surrounding said base, said 65 rocking frame including two parallel straps

connected together near their ends, rods connecting said rocking frame to the said sides, and means engaging with said rocking frame and formed on said body to permit the rocking of the lever.

70

15. A dumping body comprising a frame, a carrier body tilttable upon the frame, said body including fixed ends and movable sides, and a dumping mechanism including an operating lever, a rocking frame secured to 75 said lever, and rods connected with the ends of said frame, the rods each including a bent end for permanent engagement with the rocking frame, a straight portion normally lying along the lever end of the body, a second straight portion at right angles to the first-mentioned straight portion and normally lying along a side of the body and connected thereto, a third straight portion at right angles to the second portion and 80 normally lying along the other end of the body, a hooked terminal on said third portion, and a pin on the body end for normally holding the hooked end.

16. A dumping body comprising a frame, 90 a carrier body tilttable upon the frame, said carrier including fixed ends and bottom and movable sides, each side having legs extending to the frame below and normally resting thereupon, and an actuating mechanism, including a shiftable lever, a bent rod connecting the lever with each of the sides, said rod passing through apertures formed in said legs and rotatable therein.

95

17. A dumping body comprising a frame, 100 a carrier body tilttable upon the frame, said carrier including fixed ends and bottom and movable sides, each side having legs extending to the frame below and normally resting thereupon, said legs constituting stops to 105 limit the downward swinging movement of the sides of the body, and an actuating mechanism, including a shiftable lever, a bent rod connecting the lever with each of the sides, said rods being journaled on each 110 of the sides.

18. A dumping body comprising a frame, a body, means for supporting the body above the frame and allowing the same to be dumped to either side, said body having a 115 fixed bottom and ends and hinged sides which open outwardly and may be brought into alignment with the bottom so as to constitute a chute, means for locking the sides in closed position, and lever mechanism 120 mounted on the body and connected to the sides and the locking means, whereby either side may be unlocked and swung open without disturbing the other side.

120

19. A dumping body comprising a frame, 125 a body, means for supporting the body above the frame and allowing the same to be dumped to either side, said body having a fixed bottom and ends and hinged sides which open outwardly and may be brought 130

into alignment with the bottom so as to constitute a chute, means for locking the sides in closed position, and actuating mechanism mounted on one of the ends and including 5 an operating lever, a rocking frame carried thereby, and independent rods connected with the frame at each end and also connected to the sides, said rods terminating in

means for locking the sides in closed position.

In testimony whereof I affix my signature 10 in the presence of two witnesses.
